Inventor

Earl E. McDonald,

By Clarence A. O'Brien, Attorney

UNITED STATES PATENT OFFICE

EARL E. McDONALD, OF KIRKLIN, INDIANA

FENCE PROTECTOR

Application filed October 13, 1930. Serial No. 488,523.

This invention relates to an improved fence protector in the form of a supplemental barbed wire, and brackets for attaching said barbed wire in spaced horizontal parallelism to the line wires of a conventional wire fence.

Protecting a wire fence is a worthwhile project and unless protected in some way, the stock will ride it down by reaching through 10 to the other side, or by rubbing, stamping, or climbing on it, and in a few years it is necessary to replace the wires, if not the entire fence.

With the foregoing defects and objections 15 in mind, I have evolved and produced a simple and economical protector structure which is primarily characterized by an improved attaching bracket which is susceptible of easy application and removal on a conventional open-work wire fence.

In developing the structure for accomplishing the desired result, I have provided a bracket which can be easily and quickly placed in position and removed, which stays 25 put, holds the barbed wire properly and securely, and does not require short pieces of wire, bolts, nails, screws or other fastenings to hold it to the post or fence, or to hold the barbed wire from falling down.

A further object is to provide a bracket 20 which can be installed on any wire fence that has line wires and stay wires, regardless of the character of post used. One that can be installed anywhere desired on the fence, either high or low, at the post or between the post, and a structure which is neither a puzzle or a problem to apply and remove.

Other features and advantages will become 40 more readily apparent from the following description and drawings. In the drawings:

Figure 1 is a plan view of the bracket and barbed wire attached to the fence.

Figure 2 is an end view of the structure seen in Figure 1.

Figure 3 is a perspective view of the anchoring end of the brace.

In the drawings, the horizontal line wires are indicated by the numerals 4 and the vertical stay wires by the numerals 5. This is an ordinary wire fence construction. The

barbed wire which serves as a guard, is indicated by the numeral 6. This is also conventional.

The primary part of the bracket is designated by the numeral 7. It is formed from 55 a single length of wire bent upon itself into substantial V-shaped formation. The diverging arm portions are distinguished by the numerals 8 and 9. The intermediate or apex portion is bent into a double ply retaining hook 10 in which the barbed wire 6 seats.

The inner ends of the arms 8 and 9 are bent to permit attachment to the fence wires 4 and 5. This is accomplished by forming 65 a return bend from the wire-ends as at 11, then forming a U-shaped portion 12 to straddle the vertical wires 5 and providing a hook terminal 13 of appropriate angularity to engage over the wire 4. Thus the U-shaped part 12 embraces the wire 5 and the U-shaped 70 portions 11 and 13 engage the wire 4 on opposite sides of the wire 5 making a convenient and dependable connection.

The numeral 14 designates a substantially 75 diagonal brace which has an eye 15 at the upper end surrounding the hooked end portion of the bracket 7. In fact, this eye 15 slides beneath the bill of the hook 10 and constitutes a keeper for holding the barbed wire therein as shown in Figure 2.

The anchoring end of the brace is formed with a return bend 16 and a peculiarly shaped portion 17 having a hook terminal 18 forming an appropriate fastener or anchor for attaching the brace to the line wire as shown in 85 Figure 2. The angularity of the hook 18 is such as to provide a guard to prevent accidental displacement of the brace and to make it necessary to remove the brace manually 90 by getting it into proper angular relationship with respect to the line wire on which it is anchored.

This prevents the animals from disengaging the brace accidentally and allowing the bracket to fall.

It is thought that persons skilled in the art to which the invention relates will be able to obtain a clear understanding of the invention after considering the description in connection with the drawings. Therefore, a 100

more lengthy description is regarded as unnecessary.

Minor changes in shape, size, and rearrangement of details coming within the field of invention claimed may be resorted to in actual practice if desired.

I claim:

1. In a structure of the class described, in combination, a wire fence embodying horizontal line wires and vertical stay wires disposed in right angular intersecting relationship, a barbed wire, and means for attaching the barbed wire to the line wires of the fence comprising a bracket having a hook in which the barbed wire is engaged, and having means for detachable connection with the line wires of said fence.
2. In a structure of the class described, in combination, a wire fence embodying horizontal line wires and vertical stay wires disposed in right angular intersecting relationship, a barbed wire, and means for attaching the barbed wire to the line wires of the fence comprising a bracket having a hook in which the barbed wire is engaged, and having means for detachable connection with the line wires of said fence, and further including a brace for maintaining the bracket in a substantially horizontal barbed wire supporting position.
3. As a new product of manufacture, a barbed wire bracket for fences comprising a single length of wire bent into substantially V-shaped formation, the apex portion thereof being provided with a hook for reception of a barbed wire, the free ends of the arm portions being provided with U-shaped portions having terminal hooks for detachable connection with the line wire of the fence, and a brace having an eye co-operable with the hooked end of the bracket and provided at its opposite ends with a securing anchor for detachable connection with a line wire of the fence structure.
4. As a new product of manufacture, a barbed wire bracket comprising a single length of wire bent between its ends into a V-shaped formation, the intermediate portion thereof being formed with a double-ply hook providing a horizontally directed mouth and a horizontal seat for retention of the barbed wire, the free ends of the arms of said wire being formed with a return bend, U-shaped portions, and integral terminal hooks providing fasteners for embracing intersecting horizontal and vertical wires of a fence structure, and constituting the sole line wire anchorage.

5. As a new product of manufacture, a barbed wire bracket comprising a single length of wire bent between its ends into a V-shaped formation, the intermediate portion thereof being formed with a double-ply hook providing a seat for retention of the barbed wire, the free ends of the arms of said wire being formed with a return bend, U-shaped

portions, and terminal hooks providing fasteners for embracing intersecting horizontal and vertical wires of a fence structure, and a brace comprising a length of wire having an eye at one end embracing the hooked intermediate portion of said bracket, and provided at its opposite ends with anchoring hooks for engagement with a line wire.

6. The combination with a guard wire and a wire fence having a pair of spaced superposed line wires and a pair of spaced line wires connecting stay wires, of a guard wire support comprising a single length of wire bent into substantially V-formation, the apex portion including an integral guard wire receiving seat and the free ends having a detachable connection with the line wire at the line wire and stay wire connection and partially embracing the stay wire at the connection, and a brace wire having one end detachably mounted on the other line wire and associated with the apex portion for locking the guard wire in the seat.

7. The combination with a guard wire and a wire fence having a pair of spaced superposed line wires and a pair of spaced line wires connecting stay wires, of a guard wire support comprising a single length of wire, bent into substantially V-formation, the apex portion including an integral guard wire receiving seat and the free ends having a detachable connection with the line wire at the line wire and stay wire connection and partially embracing the line wire at both sides of the stay wire and partially embracing the stay wire at the connection, a brace wire having one end detachably mounted on the other line wire and associated with the apex portion for locking the guard wire in the seat, and brace means operatively associated with the apex portion for securing the guard wire in the seat and operatively associated with the other wire for bracing purposes.

In testimony whereof I affix my signature.

EARL E. McDONALD.
